(57) **CLAIM**

The ornamental design for an child's drinking cup with tilted floor, as shown and described.

DESCRIPTION

FIG. 1 is a right side elevational view of a child's drinking cup with tilted floor showing a first embodiment of my new design where the inside floor is shown in phantom line;

FIG. 2 is a perspective view of the first and second embodiment of a child's drinking cup with tilted floor;

FIG. 3 is a right side elevational view showing a second embodiment of my new design, with the inside floor being shown in phantom line;

FIG. 4 is a front elevational view of both the first and second embodiments;

FIG. 5 is a top plan view of the first embodiment thereof;

FIG. 6 is a bottom plan view of both the first and second embodiments thereof;

FIG. 7 is a left side elevational view of both the first and second embodiments thereof; and,

FIG. 8 is a top plan view of the second embodiment thereof. The broken line showing of the tilt of the inside floor is included for the purpose of illustrating the difference between the two embodiments.
